CLAIM

The ornamental design for a holder for hair dryer blowers, as shown and described.

DESCRIPTION

FIG. 1 is a front elevational view of a holder for hair dryer blowers showing my new design;

FIG. 2 is a left side elevational view thereof; the right side being a mirror image of the side shown;

FIG. 3 is a top plan view thereof;

FIG. 4 is a rear elevational view thereof; and

FIG. 5 is a bottom plan view thereof.

The bottom is broken away in FIGS. 1 and 4 for ease of illustration.
